(57) **CLAIM**

The ornamental design for an electric sprayer, as shown and described.

DESCRIPTION

FIG. 1 is a top perspective view of an electric sprayer, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 shows the electric sprayer in a folded state.

The broken lines depict portions of the electric sprayer that form no part of the claimed design.
